UNITED STATES PATENT OFFICE

2,650,686

TOY BANK

Emile B. Bigué, Beverly Hills, Calif., assignor to
 Bigler Manufacturing Company, Las Vegas,
 Nev., a copartnership

Application February 18, 1950, Serial No. 145,067

3 Claims. (Cl. 194—54)

1

My invention relates to toy banks and included in the objects of my invention are:

First, to provide a toy bank which receives and stores a predetermined number of coins and thereupon discharges all of the coins simultaneously.

Second, to provide a toy bank which is entertaining and amusing in its operation, therefore encourages its use.

Third, to provide on the whole a novel toy bank which is economical of manufacture and dependable in its operation.

With the above and other objects in view as may appear hereinafter, reference is made to the accompanying drawings, in which:

Figure 1 is a front view of my toy bank with a portion of the front shell member broken away to show the coin chute.

Figure 2 is a partial elevational partial sectional view thereof taken through 2—2 of Figure 1.

Figure 3 is a sectional view thereof through 3—3 of Figure 2.

Figure 4 is a fragmentary perspective view thereof with the back shell removed.

Figure 5 is a fragmentary sectional view through 5—5 of Figure 3.

Figure 6 is a fragmentary perspective view of the drum operating cam and coin retaining members.

My toy bank includes two complementary shell members 1 and 2 of substantially rectangular form. The front shell member 1 is provided with projections 3 which extend through the rear shell member 2 and are provided with rigid ends so that the two shell members may be secured together. The two shell members define a hollow upwardly extending boss 4 having a coin slot 5 therein. Below the coin slot 5 the front shell member defines a coin chute 6 covered by a back plate 7. The coin chute 6 discharges through an aperture 8 in the lower portion of the front shell member 1.

The two shell members form split journals for a drum shaft 9 which extends transversely between the sides of the shell members. Secured to, or formed integrally with the drum shaft 9, is a drum 10. The front shell member 1 is provided with a window 11 to expose a section of the drum 10. One end of the drum 10 is provided with a ring of axially extending pins 12 which form rigid elements. One of the projections or securing lugs 3 which join the shell members 1 and 2 is located in the hollow boss 4 and serves as a journal to support an escapement lever 13, having an arm 14 which extends

2

downwardly for axial movement between the pins 12. The lever 13 is provided with a second arm 15, so disposed relative to the coin slot 5 that when the proper size coin is inserted the escapement lever 13 is moved a sufficient distance to permit movement of the drum 10. One side of the arm 14 is beveled or cammed so that each pin on moving past tilts the lever 13 sufficiently to allow escape of the coin into the coin chute 6. A spring 16 disposed between the arm 14 and a recess within the boss 4, tends to maintain the lever 13 in its coin-engaging position in which the arm 15 locks the drum against rotation.

Journalized between the complementary shell members below the drum shaft 9 is an operating shaft 17, one end of which protrudes and is provided with a handle 18. Within the shell members the shaft 17 is provided with an arm 19 which is normally held against a stop 20 formed in the shell member 1 by action of a spring 21.

Journalized on the spring shaft 17 is a drum drive pawl member 22 and a coin release lever 23. These levers are urged axially on the shaft 17 by a spring 24, the release lever bearing against a stop 25. The shaft 17 is provided with a cross pin 26 which provides a drive connection between the shaft 17 and the pawl member 22. The pawl member 22 is provided with a pawl lug 27 arranged to engage the rigid pins 12. The pawl lug 27 is so beveled that on return movement of the pawl arm the member 22 is deflected by the ratchet pins and caused to slide axially against the action of the spring 24.

The coin release lever 23 is provided with an arm 28 which engages a cam lug 29 disposed adjacent one of the rigid pins 12. The lever 23 is provided with a second or latch arm 30 which extends downwardly and forwardly through a slot in the back plate 7 of the coin chute so as to engage and retain coins which have entered the chute, as shown best in Figure 1. A spring 31 tends to hold the coin release lever 23 in its coin retaining position.

Operation of my toy bank is as follows:

When a coin of proper size is inserted in the coin slot 5, the escapement lever 13 is moved sufficiently to permit rotation of the drum, thereupon, when the handle 18 of the operating shaft 17 is pulled forwardly, the pawl lug 27 engages a rigid pin 12. Rotation of the drum causes a rigid pin 12 engaging the cam arm 14 of the escapement lever to pivot the lever further, releasing the coin, so that subsequently the lever returns to its locking position between the rigid pins. The handle 18 returns by spring action

to its original position and the pawl lug 21 is deflected past a ratchet pin, so as to be in position for another operation. As each coin is inserted, the drum is advanced an amount predetermined by the ratchet pins 12. When the cam lug 29 engages the arm 28 of the coin release lever 23, operation of the handle 18 causes the release arm to clear the coins and permit those coins which have accumulated in the coin chute 6, to discharge through the aperture 8.

The drum is provided with suitable indicia exposed in succession at the window as the drum is rotated.

Having fully described my invention, it is to be understood that I do not wish to be limited to the details herein set forth, but my invention is of the full scope of the appended claims.

I claim:

1. A toy bank, involving: a housing defining a generally vertically extending coin chute, a coin receiving slot at the upper end of the chute, and a discharge aperture at the lower end of the chute; a coin operated latch near the coin receiving slot; an indicia bearing drum rotatable in said housing and having a ring of axially directed pins at one end; said latch having an end, adapted to enter between said pins to restrain said drum, and movable to free said drum on insertion of a coin in said receiving slot; a countershaft oscillatably mounted in said housing and having an exposed end; a handle for said exposed end; a pawl means mounted on said countershaft and engageable with said pins to advance said drum on oscillation of said handle; a coin restraining lever journaled on said countershaft and including an end extending into said coin chute near its discharge aperture to restrain coins therein and an end extending in proximity to said ring of pins; and a cam member on said drum disposed to engage said coin restraining lever to release coins accumulated in said chute.

2. A toy bank, involving: a housing defining a generally vertically extending coin chute, a coin receiving slot at the upper end of the chute, and a discharge aperture at the lower end of the chute; a coin operated latch near the coin receiving slot; an indicia bearing drum rotatable in said housing and having a ring of axially directed pins at one end, said latch having an end, adapted to enter between said pins to restrain said drum, and movable to free said drum on insertion of a coin in said receiving slot; a countershaft oscillatably mounted in said housing and

5 having an exposed end; a handle for said exposed end; a pawl means axially slidably mounted on but oscillatable with said countershaft, said pawl means operatively engageable with said pins on oscillation of said countershaft in one direction to advance said drum, said pawl being cammed by said pins and axially slidable on said countershaft to pass one of said pins on oscillation of said countershaft in the opposite direction; a coin restraining lever journaled on said countershaft and including an end extending into said coin chute near its discharge aperture to restrain coins therein and an end extending in proximity to said ring of pins; and a cam member on said drum disposed to engage said coin restraining lever to release coins accumulated in said chute.

3. A toy bank, involving: a housing defining a generally vertically extending coin chute, a coin receiving slot at the upper end of the chute, and a discharge aperture at the lower end of the chute; a drum journaled in said housing and having a ring of axially directed pins; a coin operated latch having a coin engaging end projecting into said chute near its coin receiving slot and a cammed end normally fitting between said pins to restrain said drum and axially movable to clear said pins, said latch movable to an intermediate position by a coin inserted in said chute wherein said pins are engageable with the cammed end of said latch to free said drum, said latch thereupon being movable by said pins to an extreme position on rotation of said drum thereby to release said coin, said latch thereafter returning to its normal restraining position; a manually operated pawl means for advancing said drum when freed by insertion of a coin; a second latch having a coin restraining end adjacent the discharge end of said chute, and a trigger end adjacent said drum; and means on said drum for engaging said trigger end to release said second latch and discharge the contents of said chute on predetermined rotation of said drum.
